DESIGN FOR AN ARMORED AUTOMOTIVE VEHICLE

Carroll M. Smart, Detroit, Mich., assignor to
Smart Safety Engineering Company, Detroit,
Mich., a corporation of Michigan

Application March 3, 1943, Serial No. 109,655

Term of patent 14 years

(Cl. D14—3)

To all whom it may concern:

Be it known that I, Carroll M. Smart, a citizen of the United States and a resident of Detroit, in the county of Wayne and State of Michigan, have invented a new, original, and ornamental Design for an Armored Automotive Vehicle, of which the following is a specification, reference being had to the accompanying drawing forming a part thereof.

In the drawing:

Fig. 1 is a front elevational view of an armored automotive vehicle showing my new design;

Fig. 2 is a rear elevational view; and

Fig. 3 is a top plan view thereof.

I claim:

The ornamental design for an armored automotive vehicle, substantially as shown.
